SEAL FOR WELL TUBING

Edward N. Jones, Pettus, Tex.

Application June 28, 1948, Serial No. 35,571

6 Claims. (Cl. 166—2)

1

This invention relates to improvements in seals for well tubing, and more particularly to devices for temporarily sealing a string of casing, tubing or other pipe in an oil well, as while the string is being lowered into a borehole containing fluids, and for temporarily restricting the upward flow of fluid through the string after the seal is broken, as when completing the well.

An important object of this invention is the provision of means for speedily completing a well while maintaining controls over the fluids under pressure therein.

Another object of this invention is the mounting in juxtaposition in a well tubing of a rupturable sealing member and an erodible choke or restrictor member, whereby flow of fluids under pressure through the tubing can be prevented as long as desired and then restricted until the pressures above and below the choke member have been substantially equalized, permitting use of the usual ground flow control equipment to control the further flow of well fluids.

A further object of this invention is the coaction of temporary sealing means for well tubing and means for breaking the seal whenever desired, substantially all of which will be removed from the well by the flow of well fluids through the tubing subsequently to the breaking of the seal.

Further objects and advantages will be apparent from the following description taken in connection with the accompanying drawings showing presently preferred embodiments of my invention.

In the drawings:

Fig. 1 is a longitudinal section of one form of my improved seal.

Fig. 2 is a fragmentary section of another form thereof.

Fig. 3 is a longitudinal section of a penetration tool for rupturing the seal, and

Fig. 4 is a longitudinal section of still another form of my improved seal.

In the form of the device shown in Fig. 1, there is provided a sleeve or shell 1 with terminal male elements 1a and 1b exteriorly threaded for engagement with interiorly threaded female members 2a and 3a of tubing sections 2 and 3, respectively.

The upper element 1a is provided in its outer face with an annular, inner peripheral seat 4 providing an annular, outer peripheral flange 5. Fitting in the seat 4 is a plate 6 of suitable material, such as sheet metal, and having such diameter and thickness as to conform nicely with

2

the seat 4, so that when shell 1 is set up in section 2, the flange 5 and plate 6 are clamped against the end of section 2 by the screw action of the co-acting threaded parts to effect a sealed joint between shell 1 and tubing section 2. The sleeve 1 is interiorly enlarged to provide a receptacle 7 and a shoulder 8 for a choke plug 9 of suitable, easily erodible material, such as magnesium, and which is immobilized in the receptacle 7, between the shoulder 8 and section 3, when the section is set up on the shell 1. Choke plug 9 has a longitudinal, axial bore 10 of comparatively small initial diameter, but which is rapidly enlarged as the flow of fluids therethrough proceeds, as hereinafter described.

In the form of the device shown in Fig. 2, the sleeve 11 has a terminal male element 11a with a plane outer end 11b engaging a plate 12, of suitable, easily erodible material, such as magnesium, seated in the section 13. It will be noted that the parts are so dimensioned that when the shell 11 is set up in the section 13 and bears against the plate 12 there remains a slight gap G, in which is fitted a suitable washer W, between the outer end of the section 13 and the unthreaded portion of the shell 11, so that the plate 12 is clamped between the shell 11 and the section 13 by the screw action of the co-acting threaded parts to effect a sealed joint therebetween.

The female member 13a in which is received the male member 11a has a set-screw 14 to immobilize the assembled parts in such sealed relation. The plate 12 has annular grooves 12a or the like cut in its upper and lower surfaces to provide a weakened portion 12b and a guide for retaining acid or the like in engagement with such weakened portion when the seal is to be broken.

40 The penetration tool T, shown in Fig. 3, has a shell 15 of suitable, easily erodible material, such as magnesium, a cap 16 of the same material and a suitable cutting head 17. The shell 15 is preferably loaded with a charge 18 of suitable liquid of high specific gravity, such as mercury, to provide sufficient weight to insure proper functioning of the tool T.

45 In the form of the device shown in Fig. 4, the shell 20 has a shoulder 21 against which is seated a choke plug 22 snugly fitted in the shell 20 and having a reduced portion 22a provided with packing means to effect a sealed joint between the shell 20 and the plug 22. Any suitable packing means may be employed to provide a seal 50 between the choke plug and shell 20 such as

O-rings, chevron packing or the like. In the embodiment of the drawings, the packing means comprises a pair of packing rings 23 and a pair of collars 24 and 25 about the reduced portion 22a. The rings 23 are of any suitable material and frusto-conical in cross-section to provide convergent faces 23a, 23b. Each ring 23 has an interior flange 23c fitted closely about the portion 22a to provide annular spaces about the portion 22a to receive therein the sleeve portions 24a and 25a of the collars 24 and 25, respectively, their ends bearing on the flanges 23c, respectively. The face 23a of the ring 23 disposed at the inner end of the portion 22a is juxtaposed with an inclined annular flange 22b on the plug 22, and the face 23b of this ring is juxtaposed with an inclined annular flange 24b on the collar 24. The collar 24 has a plurality of grooves 24c in the outer surface of the sleeve portion 24a connected respectively with a plurality of bores 24d, debouching into the space between the reduced portion 22a and the shell 20.

The face 23a of the ring 23 disposed toward the outer end of the portion 22a, is juxtaposed with an inclined annular flange 25e on the collar 25, and the face 23b of this ring is juxtaposed with an inclined face 25b of the collar 25. The collar 25 has the grooves 25c and bores 25d identical with those above-mentioned.

A follower 26 is threaded on the lower end of the portion 22a and serves to force the interposed washer 27 against collars 25 and 24 to apply expanding pressure to the rings 23 to effect a seal between the shell 20 and plug 22.

The plug 22 has a longitudinal axial bore 28 debouching at the lower end of the portion 22a and having its upper end spaced from the upper end of the plug 22 which has a central depression 22c whereby a closed portion 28a is formed between the upper end of the bore 28 and the depression 22c.

The container 29, a fragment of which is shown in the upper part of Fig. 4, is designed for a suitable acid (not shown) for attacking the seal member (12 of Fig. 2 and thin part of 22 of Fig. 4). The container 29 is provided in its bottom with a check valve 30 having a head 31 projecting outwardly of the container 29.

I will now explain the use and operation of the several forms of my improved device which have been hereinbefore fully described.

The device shown in Fig. 1 is assembled and functions as follows. The tubing section 2 is threaded into or near to the lower end of a string of tubing. The plate 6 is placed in the seat 4 of the shell 1 and the shell 1 is set up in the section 2 to clamp the plate 6 between the shell 1 and section 2 in a sealed joint to effectively close the channel in the string of tubing. The choke plug 9 is then placed in the receptacle 1 of the shell 1 and the section 3 is set up on the shell 1 to clamp the plug 9 between the shoulder 8 of shell 1 and section 3. The device, thus assembled as shown in Fig. 1, is conditioned to function. The section 3 may be provided with a suitable screen (not shown) to protect the device from debris which might otherwise collect in the section 3 and block off the bore 16 in plug 9.

The string of tubing is sufficiently lowered into the well bore to dispose the shell 1 at the proper point for opening the channel through the string of tubing.

The flow connections are made at the ground surface to control the flow of the well fluids. The penetration tool T (Fig. 3), dropped free or low-

ered by a wire through the string of tubing, impinges upon the plate 6 with such force that its cutting head 17 punctures the plate 6 to break the seal of the channel through the string of tubing. The well fluids will enter the tubing due to the pressure differential across plate 6. As the fluids are forced by this pressure through the bore 10, the plug 9 becomes rapidly eroded by their passage therethrough due to the mechanical action of the abrasive matter in the fluids and also due to the corrosive action due to acidic materials in the fluids. It is obvious that the choke plug 9 thus controls the rate of flow of the well fluids until the pressures above and below the device become equalized. This condition becoming established, the ground flow control equipment functions to control the rate of flow of the well fluids.

It is obvious that the flow of the fluids will rapidly disintegrate the casing 15 and cap 16 of tool T, releasing the fluid 18 to mingle with the well fluids, thereby eliminating the tool T as an obstruction in the tubing after it has functioned.

The device shown in Fig. 2 is assembled as the device of Fig. 1 above described and the set-screw 14 is set up to lock the sleeve 11 in the section 13. The plate 12 is punctured by pouring a suitable acid down the string of tubing or supplying it by the receptacle 29 (Fig. 4) lowered to strike plate 12, the head 31 striking the plate 12 to release valve 30 to allow the acid to flow out of the container 29. The acid, supplied in either of these ways, accumulating in the groove 12a, on the upper surface of the plate 12, attacks the reduced thickness of the material of the plate 12 quickly severing the weakened portion 12b to rupture plate 12. The plug 9 of this form of the device functions as above described and the annular portion of plate 12 is also eroded by the passage therethrough of the well fluids, to eliminate any obstruction in the tubing.

The device shown in Fig. 4 is assembled by mounting rings 23 and collars 24 and 25 on the portion 22a of the plug 22 and holding them thereon by the washer 27 and follower 26 which is as yet not set up to expand rings 23. The assembled parts are then mounted in sleeve 20 the plug 22 being seated on the shoulder 21. The follower 26 is then set up urging collars 24 and 25 to expand rings 23 to effect a sealed joint between sleeve 20 and plug 22. The sleeve 20 is then introduced in the string of tubing at the desired point thereof.

It will be noted (Fig. 4) that the bores 24d, 25d and the grooves 24c, 25c of the collars 24 and 25 afford passages through which pass the well fluids under pressure flow to exert expanding force upon the packing rings 23 to augment their sealing action.

When the receptacle 29 is dropped or lowered through the tubing to impinge on the plug 22 the acid in the container flows therefrom into the depression 22c on the top face of the plug 22. If convenient the acid may be poured down the tubing without use of the container 29. The acid, supplied in either of these ways, accumulating in the depression 22c, attacks the thin web of the plug 22 between the receptacle 22c and the upper end of the bore 28, and rapidly eats through this web to open the bore 28 to admit the well fluids therethrough to the string of tubing. The choke plug 22 then functions as plug 9 as above described.

The Fig. 4 device is preferred for it may be forced downwardly out of shell 20 and the tubing connected to the lower end thereof by applying

pressure to the upper face of member 22 to break the seal and remove the plug if this should become desirable, as for instance: in the event of a blow out, to permit circulation of drilling fluids to establish control; or to permit completion of the well if bore 28 should become plugged with debris when the tubing is lowered within a well bore. Also with this structure the thickness of the material of the choke plug 22 to be destroyed by acid to make the tool function may be less than in the Fig. 2 modification providing faster action.

As many possible embodiments may be made of the invention without departing from the scope thereof, it is to be understood that all matter herein set forth or shown in the accompanying drawings is to be interpreted as illustrative and not in a limiting sense.

Having described my invention what I claim is:

1. In a seal for well tubing, the combination of a sleeve having means for mounting said sleeve to form a part of the tubing, a choke plug in said sleeve and having a reduced portion with an axial bore extending within the reduced portion, a closure closing the upper end of the bore and constructed of acid-dissolvable material, a central depression in the upper end of said closure adapted to confine acid inserted above the plug to direct the dissolving of the closure to that portion thereof above the axial bore, a packing ring, expandable radially of said portion, an expanding collar, axially movable on said portion, and means on said portion for moving said collar to expand said ring to effect a seal between said sleeve and said plug.

2. In a seal for well tubing, the combination of a sleeve having means for mounting said sleeve to form a part of the tubing, a choke plug in said sleeve and having a reduced portion with an axial bore extending within the reduced portion, a closure closing the upper end of the bore and constructed of acid-dissolvable material, a central depression in the upper end of said closure adapted to confine acid inserted above the plug to direct the dissolving of the closure to that portion thereof above the axial bore, a packing ring, expandable radially of said portion, an expanding collar, axially movable on said portion, and means on said portion for moving said collar to expand said ring to effect a seal between said sleeve and said plug, said collar being provided with conduits for fluid under pressure, said conduits being positioned to supply said fluid to said ring to augment its sealing action.

3. In a seal for well tubing, the combination of a sleeve having means for mounting said sleeve to form a part of the tubing, stop means interiorly of the sleeve, a choke plug within the sleeve on one side of the stop, seal means providing a seal between the plug and sleeve and a passage in the plug extending axially substantially but not quite the length of the plug, a cen-

tral depression in the upper surface of the plug, a thin web of material between said depression and said passage, whereby acid may accumulate in said depression for dissolving said web to open said passage at its upper end.

4. In a seal for well tubing, the combination of a sleeve having means for mounting said sleeve to form a part of the tubing, a choke plug mounted within the sleeve and comprising a cylindrical body having an axial bore extending from its lower end to a point spaced from the top of the body whereby the upper end of the bore is closed by a relatively thin section of the material of which the body is constructed, the body being constructed of an acid-dissolvable and erodible material and having a central depression in its upper end over said thin section of material, whereby the upper end of the bore may be opened by dissolving the material closing said bore with acid after which the body will be eroded by flow therethrough, and means carried by the exterior of the plug for sealing between the plug and the sleeve within which said plug is mounted.

5. The combination set forth in claim 4, where-
25 in the sealing means comprises annular packing rings with means for admitting the pressure from below the plug within said rings to assure seal-
ing contact of the rings with the inner wall of the sleeve.

30 6. In a seal for well tubing, the combination of a sleeve having means for mounting said sleeve to form a part of the tubing, a choke plug in said sleeve, means for retaining said plug in said sleeve, said plug comprising a cylindrical body
35 having an axial bore extending from its lower end to a point spaced from the top of the body, a central depression in the upper end of said body, a thin web of material between said de-
pression and said axial bore, whereby acid ad-
40 mitted into said tubing above said plug is con-
fined in said depression to dissolve said thin web for opening the upper end of said axial bore so that well fluids may pass therethrough from
below said plug to the tubing thereabove.

45 EDWARD N. JONES.
